UNITED STATES PATENT OFFICE.

DAVID S. HULFISH, OF TORONTO, ONTARIO, CANADA, ASSIGNOR TO CANADIAN INDEPENDENT TELEPHONE COMPANY, LIMITED, OF TORONTO, CANADA, A CORPORATION OF CANADA.

AUTOMATIC TELEPHONE SYSTEM.

1,118,490.

Specification of Letters Patent. Patented Nov. 24, 1914.

Application filed March 23, 1911, Serial No. 616,831. Renewed April 8, 1914. Serial No. 830,538.

To all whom it may concern:

Be it known that I, DAVID S. HULFISH, a citizen of the United States of America, and a resident of Toronto, county of York, Province of Ontario and Dominion of Canada, have invented a new and useful Improvement in Automatic Telephone Systems, of which the following is a specification.

My invention relates to automatic telephone systems and has as its principal object to provide a simple and efficient means whereby any one of a plurality of subscribers' sub-stations may be automatically connected to a trunk line, the station during its connection being guarded from interference by any other sub-station attempting to obtain connection with the trunk.

A further object of my invention consists in providing a busy tone in the receiver of a sub-station attempting to connect with the trunk while the latter is busy.

A further object of my invention consists in providing a system of inter-connected relays of which but one may be operated at any one time.

I accomplish these and other desiderata hereinafter disclosed by a novel system of relays and circuits whereby the telephone lines are normally maintained in connection with a busy tone circuit and are automatically switched from such connection to the trunk circuit by the removal of the receiver from the hook at the subscriber's station first calling, the remaining sub-stations being locked in connection with the busy tone circuit during conversation over the trunk line by any one of the sub-stations.

In the figures which accompany and form a part of this specification and in which like numerals designate corresponding parts throughout: Figure 1 illustrates in diagram four subscribers' sub-stations and a trunk line showing apparatus and circuit arrangements embodying my invention. Fig. 2 illustrates the apparatus and circuit arrangement of Fig. 1 and shows a sub-station in talking connection with the trunk line.

Referring to the figures, any number of subscribers' sub-stations, four of which I have illustrated for convenience at 1, 2, 3 and 4, are connected through the usual terminal and protective apparatus, which as it is so well known in the art is omitted from the diagram to avoid unnecessary complication, to a strip of jacks 7, 27 for purposes of

manual switching. The ring or long-spring contacts of the jacks 7, 27 are connected to one of the outside terminals of the A sides of repeating coils 21, 51 respectively, the corresponding middle terminals of the A sides of the repeating coils being connected to the battery 200 through the respective battery bus wires 18 and 19. The tip or short-spring contacts of the jacks 7, 27 are connected through the series relays 8, 28 respectively to the remaining outside terminals of the A sides of repeating coils 21, 51. The B' side of the repeating coils 21, 51 have their inner terminals connected together and their outside terminals connected to the talking armatures of relays 10, 50 respectively. The back contacts 13, 16 and 53, 56 of relays 10, 50 are connected to a pair of normal conductors 76 and 77 respectively over which the busy tone is supplied, thus normally placing the busy tone on the B sides of repeating coils 21, 51. The front contacts 14, 15 and 54, 55 of relays 10, 50 are connected to trunk conductors 75 and 74 respectively, thereby bridging the B sides of a repeating coil as 51, 80 across the trunk line when relay 50 is energized. The armatures of the series relays 8, 28 are connected through conductors 17, 57 with terminals of both the windings of relays 10, 50 respectively, while the front contacts 9, 29 of relays 8, 28 respectively are grounded at 24, 43 respectively.

Relays 10, 50 are connected through one of their other terminals with conductor 22 while the remaining terminals of the relays 90 are connected to contacts 11, 61 of their respective relays. The contact, as 11, is arranged to be made by the operation of the signaling armature of a relay as 10, before contact 12 is broken by the same operation 95 of the signaling armature. The signaling armature of relay 10 is connected to conductor 22, while the back contact of the same is connected through conductor 45 with the signaling armature of relay 30. Similarly 100 the back contact of the signaling armature of a preceding relay is connected to the signaling armature of the next succeeding relay until the back contact of a signaling armature of the last relay as 50, in a group of 105 relays, is reached, which has the back contact of its signaling armature connected through conductor 23 and battery bus wire 18, to grounded battery 200.

The broken line C—C indicates that any 110

number of sub-stations may be provided with trunking apparatus and circuits similar to those shown for sub-stations 2 and 3, while the dotted extension of conductors 18, 19, 22, 76, 77, 75, 74 and the dotted conductor 42 indicate that the circuits at the central office for station 4 may be modified by the removal of conductor 23 and more sets of apparatus added, conductor 23 however being connected as shown in the circuit of the last group of apparatus added.

Referring to Fig. 2 in which the circuits are shown in an operated condition to allow station 4 to gain talking connection with the trunk line, the removal of the receiver from the hook at sub-station 4 closes a circuit through the sub-station line conductors, battery bus wires 18 and 19 with battery 200 which energizes relay 28 causing it to operate its armature to make contact through front contact 29 between ground 43 and conductor 57, thus placing ground upon the windings of relay 50 and closing a circuit through left helix of the winding of relay 50, conductor 22, signaling armature of relay 10, back contact 12 of relay 10, conductor 45, signaling armature and back contact 32 of relay 30, conductor 46, signaling armature and back contact 42 of relay 40, conductor 47, to signaling armature and back contact 52 (not yet operated, see Fig. 1) of relay 50, conductor 23, battery bus 18 to grounded battery 200, thus energizing relay 50 to break contact between its talking armatures and busy tone contacts 53 and 56, thus removing the calling line from the busy tone circuit and making contact between its talking armatures and front contacts 54 and 55, thus placing the line in talking connection with the trunk line 74, 75. Simultaneously with the operation of the talking armatures, the signaling armature of relay 50 is operated to make contact with front contact 61 before back contact 52 is broken, thus maintaining the energizing circuit for relay 50 through one helix of its winding as hitherto noted until front contact 61 is closed and back contact 52 is finally broken, thereby providing an alternative energizing path for relay 50 from ground 43, contact 29 of series relay 28, conductor 57, right helix of relay 50, front contact 61 of the signaling armature of relay 50, contact 52, conductor 23, battery bus 18 to grounded battery 200, thus holding relay 50 energized and maintaining the connection of sub-station 4 with the trunk line.

Should a subscriber at another sub-station as 1, attempt to obtain connection with the trunk line being held by a sub-station as 4, and in initiating the connection remove the receiver at station 1 from the hook, current will flow from battery 200, through the closed bridge at station 1, thus energizing series relay 8 to close its front contact and place ground 24 through contact 9 of relay

8 upon the following incomplete circuit. Conductor 17, left helix of relay 10, to and through conductor 22, branch conductor 20, signaling armature and back contact 12 of relay 10, conductor 45, signaling armature and back contact 32 of relay 30, conductor 46, signaling armature and back contact 42 of relay 40, conductor 47, to signaling armature of relay 50 at which point the circuit is broken as relay 50 is energized and its back contact 52 is therefore open from the armature and ground 24 does not meet grounded battery 200. Thus relay 10 is not energized and the subscriber at sub-station 1 attempting to connect with the busy trunk line receives through the back contacts of relay 10 the busy tone in his receiver, indicating to that subscriber that the trunk line is busy. Similarly a subscriber at any sub-station will hear the busy tone in his receiver when attempting to connect his instrument with a busy trunk.

The taps 17, 57 of the windings of relays 10 and 50 to ground through series-relay contacts 9, 29 respectively are of substantially zero resistance, for should a series relay as 8, be operated to close its contact as 9, by the removal of the receiver at the subscriber's sub-station as 1, in an attempt on the part of the subscriber to connect his instrument with a trunk line being held by another station as 4, the tap 57 from the winding of relay 50 to ground 43, through contact 29 will be shunted by the circuit: left helix of relay 50, conductor 22, left helix of relay 10, conductor 17, contact 9 of series relay 8 to ground 24. As this shunt contains two left helices of the windings of relays 10 and 50, it is of relatively high resistance compared to the resistance to ground from the right winding of relay 50 through conductor 57, and as the tap 57 to ground 43 through contact 29 of series relay 28 is substantially zero in resistance, it follows that substantially all of the current from grounded battery 200 through battery bus 18, conductor 23 and right helix of relay 50 flows to ground through the ground tap 57 and the right helix of relay 50 instead of through the left helix of relay 50, conductor 22 to ground through conductor 17 and contact 9 of relay 8.

It will be noted that should a subscriber remove his receiver from the hook in attempting a connection with the trunk and find the trunk busy, he may hold his receiver removed from the hook and automatically obtain connection with the trunk the instant the subscriber holding the trunk releases the same by hanging up his receiver, for the operation of replacing the receiver upon the hook at the termination of a conversation over the trunk line, releases the series relay as 28, thereby breaking the energizing circuit of relay 50 which

allows its talking and signaling armatures to return to normal, removing the sub-station as 4, from the trunk line and replacing it on the busy tone circuit and simultaneously allowing the energization of relay as 10, which removes the busy tone from the receiver of the subscriber attempting the call and places that subscriber in talking connection with the trunk as hitherto explained.

It will be further noted that as both relays as 8 and 10 are quick-acting, the busy tone will not be perceptibly manifest in the receiver of a sub-station making connection with a trunk as the operation of the hook switch in bridging the instrument to the line and the operation of relays as 8 and 10, are substantially simultaneous.

While I have disclosed but one embodiment of my device, it is obvious that numerous changes may be made in the apparatus and circuits thereof without departing from the spirit or narrowing the scope of my invention.

Having thus described my invention, what I claim as new and desire to secure by United States Letters Patent is as follows:

1. In an automatic telephone system, a plurality of telephone lines; a tone circuit; said telephone lines being normally connected to said tone circuit; a trunk line; and means for disconnecting any one of said telephone lines from said tone circuit and for connecting said telephone line to the said trunk circuit.

2. In an automatic telephone system, a plurality of telephone lines; a tone circuit; said telephone lines being normally inductively connected to said tone circuit; a trunk line; and means for automatically disconnecting any one of said telephone lines from said tone circuit and connecting said telephone line to said trunk circuit.

3. In an automatic telephone system, a plurality of telephone lines, a busy tone circuit, said telephone lines being normally connected to said busy tone circuit, a trunk line, means for disconnecting any one of said telephone lines from said busy tone circuit and connecting said telephone line to said trunk line, means co-operative with said trunk line, means co-operative with said previously mentioned means for guarding said telephone line during connection with said trunk line from interference by any other telephone line attempting connection with said trunk line.

4. In an automatic telephone system, a plurality of telephone lines, a busy tone circuit, said telephone lines being normally inductively connected to said busy tone circuit, a trunk line, means for automatically disconnecting any one of said telephone lines from said busy tone circuit and connecting said telephone line to said trunk

circuit and means co-operative with said previously mentioned means for guarding said telephone line during connection with said trunk line from interruption by any other telephone line attempting connection with said trunk line.

5. In an automatic telephone system, a plurality of telephone lines, a plurality of relays at the central office each associated with one of said telephone lines, a busy tone circuit, said telephone lines being each normally connected to said busy tone circuit through contacts of its said associated relay, means for automatically operating one of said relays to break contact between its associated telephone line and said busy tone circuit and through other contacts on said relays place said telephone line in connection with said trunk line.

6. In an automatic telephone system, a plurality of telephone lines, a plurality of relays at the central office each associated with one of said telephone lines, a tone circuit, said telephone lines being each normally connected to said tone circuit through contacts of its said associated relay, means for automatically operating said relays to break contact between said telephone lines and the tone circuit and through other contacts on said relays place said telephone line in connection with said trunk line, and means co-operative with said previously mentioned means for guarding said telephone line during connection with said trunk line from interference by any other telephone line attempting connection with said trunk line.

7. In an automatic telephone system, a plurality of telephone lines, a plurality of relays at the central office each inductively associated with one of said telephone lines, a tone circuit, said telephone lines being each normally inductively connected to said tone circuit through contacts of its said associated relay, means for automatically operating said relays to break contact between any one of said telephone lines and said inductively connected tone circuit and through other contacts on said relays place said telephone line in connection with said trunk line.

8. In an automatic telephone system, a plurality of telephone lines, a plurality of relays at the central office each inductively associated with one of said telephone lines, a busy tone circuit, said telephone lines being each normally inductively connected to said busy tone circuit through contacts of its said associated relay, means for automatically operating said relays to break contact between any one of said telephone lines and said inductively connected busy tone circuit and through other contacts on said relays place said telephone line in connection with said trunk line, and means co-

- 4
- operative with said previously mentioned means for guarding said telephone line during connection with said trunk line from interference by any other telephone line attempting connection with said trunk line.
9. In a telephone system, a plurality of telephone lines; a pair of normal wires upon which said lines are concentrated and normally interconnected; a trunk circuit normally dissociated from said lines, and a relay controlled by one of said lines and adapted to remove its line from said normal pair to said trunk circuit.
10. In a telephone system, a plurality of telephone lines; a pair of normal wires upon which said lines are concentrated and normally interconnected; a trunk circuit normally dissociated from said lines; a relay for each of said lines switching the line from the normal pair to the trunk circuit, each relay controlled from its line; and a circuit pertaining to all said relays and acting to permit the energization of but one relay at a time.
11. In a telephone system, a plurality of telephone lines; a pair of normal wires upon which said lines are concentrated and normally interconnected; a trunk circuit normally dissociated from said lines; a relay for each of said lines and acting to switch the line from the normal pair to the trunk circuit; means for energizing one of said relays; and contacts within said energized relay for preventing the energization of any other relay.
12. In a telephone system, a plurality of telephone lines; a pair of normal wires upon which said lines are concentrated and normally interconnected; a trunk circuit normally dissociated from said lines; a relay for each of said lines; means for initially energizing one of said relays; and contacts
- forming a part of said relay for preventing the energization of any other relay and for continuing the energization of the energized relay so long as the initial energizing means maintains its condition which initiated the energization.
13. In a telephone system, a tone circuit; telephone lines normally connected thereto; a trunk circuit; means for switching said lines from said tone circuit to said trunk circuit; and further means preventing the switching of a plurality of said lines simultaneously.
14. In a telephone system, a tone circuit; telephone lines normally connected thereto; a trunk circuit; means for switching said lines from said tone circuit to said trunk circuit; said means being operated to remove a line from said tone circuit only when said trunk circuit is disconnected from all lines.
15. In a telephone system, a series of relays, means for energizing any one of said relays initially, and an interference circuit pertaining to all said relays and operating to prevent the operation of two of said relays simultaneously.
16. In a telephone system, a series of relays and means for energizing any one of them initially, said means comprising, in part a circuit passing through normally closed pairs of contacts, one pair in each relay, said pairs in series in said circuit, and said circuit passing thence to windings of all of said relays, in multiple.

Signed by me at Toronto, county of York, and Province of Ontario, in the presence of two witnesses.

DAVID S. HULFISH.
